[57] CLAIM

The ornamental design for a dual removable blade ice scraper, substantially as shown and described.

DESCRIPTION

FIG. 1 is a side view of a dual removable blade ice scraper showing my new design;

FIG. 2 is a top elevational view thereof;

FIG. 3 is an end view thereof, taken from the left of FIG. 1; and

FIG. 4 is an end view thereof taken from the right of FIG. 1.

The handle is shown fragmentarily in FIGS. 1 and 2 for ease of illustration.

In FIG. 1 the pattern of bristles is understood to repeat uniformly and continuously across the entire indicated area.
